The ornamental design for a guide rail for an overhead monorail, as shown.

DESCRIPTION

FIG. 1 is a top plan view of a guide rail for an overhead monorail showing my new design;

FIG. 2 is a front elevational view thereof;

FIG. 3 is a bottom plan view thereof;

FIG. 4 is a rear elevational view thereof;

FIG. 5 is a right end elevational view thereof, the left end being a mirror image of that shown;

FIG. 6 is a cross sectional view thereof taken along line 6—6 in FIG. 2; and,

FIG. 7 is a perspective view thereof.
